Inventor
George H. Reoch,
By his Attorney C. P. Gofel

UNITED STATES PATENT OFFICE.

GEORGE H. REOCH, OF BROOKLYN, NEW YORK, ASSIGNOR TO THE INTERNATIONAL POSTAL SUPPLY COMPANY, OF BROOKLYN, NEW YORK, A CORPORATION OF NEW YORK.

PRINTING DIE.

Application filed November 28, 1922. Serial No. 603,737.

To all whom it may concern:

Be it known that I, GEORGE H. REOCH, a citizen of the United States, and a resident of Brooklyn, county of Kings, and State 5 of New York, have invented certain new and useful Improvements in Printing Dies, of which the following is a specification.

This invention relates to an improved printing die and more particularly to a die 10 of that character especially designed for use in connection with post office stamp cancelling machines. My present improvements, however, are not necessarily limited in their utility to such machines, as the improved die 15 is one of more or less general application which might be adapted for use in connection with other printing machines and employed for various purposes.

Generically considered, the invention has 20 for its primary object to provide a printing die having a plurality of changeable type carrying bars, means for releasably locking the associated type bars in fixed position relative to the die body, and means acting 25 to automatically project the type bars from the face of the die body when the locking means is moved to position to release said bars so that such type bars can be easily grasped and removed and replaced by 30 others. The invention further contemplates the provision of a printing die for stamp cancelling machines wherein the die body is suitably mounted upon and carried by an oscillating hub or die holder and means for 35 releasably holding the changeable type bars in connection with the die body as above explained which can be readily actuated when it becomes necessary to change the type bars without requiring the removal of the 40 die from the oscillating hub or holder.

It is also a further general object of the invention to provide a printing die as above characterized the several parts of which are 45 of simple and durable construction, compactly arranged and not liable to get out of order and which will not materially add to the manufacturing cost of such dies or the machines upon which they are used.

With the above and other objects in view, 50 the invention consists in the improved printing die and in the form, construction and relative arrangement of its several parts as will be hereinafter more fully described, illustrated in the accompanying drawing

and subsequently incorporated in the sub- 55 joined claims.

In the drawing wherein I have illustrated one practical and satisfactory embodiment of the present invention and in which similar reference characters designate corresponding parts throughout the several views:

Figure 1 is a plan view of the improved printing die and the holder upon which it is mounted;

Figure 2 is a side elevation thereof;

Figure 3 is an enlarged sectional view taken on the line 3—3 of Figure 1;

Figure 4 is a rear end elevation of the die removed from its holder;

Figure 5 is an enlarged detail section 70 taken on the line 5—5 of Figure 4;

Figure 6 is a detail perspective view of the die body;

Figure 7 is a detail perspective view of the day and hour type bars; and

Figure 8 is a similar view of the month and year type bars.

In the accompanying drawing I have illustrated a printing die constituting the subject matter of this application, mounted 80 and arranged upon an oscillating hub or die holder of conventional form. Since this new printing die may be employed in connection with various types of stamp cancelling machines or printing machines employed for other purposes, the specific description of the machine as a whole would be superfluous. Accordingly, I have shown and will refer only to such parts of the printing mechanism as are requisite to a 85 clear understanding of the application and use of my present improvements.

To the above end, therefore, I have indicated in the accompanying drawing the oscillatable hub or die holder 5 which is suitably mounted upon a shaft or arbor 6 and intermittently actuated by any approved mechanism with which the machine may be equipped. This die holder 5 carries the usual number of spaced curved metal plates 100 or fins 7 which are employed for the purpose of imprinting or marking upon the postage stamp on the envelope, a plurality of parallel wavy or curved cancellation lines, with which the general public is entirely familiar.

In the application and use of my present improvements, I preferably provide a cylind-

drical recess or chamber 8 in one side of the die holder 5. The die body 9, as herein shown, is in the form of a metal disc having a convex printing face substantially concentric with the axis of oscillation of the die holder 5. The opposite side of the die body is formed with a reduced exteriorly cylindrical boss or extension 10 which is adapted to be snugly fitted within the chamber or recess 8 of the die holder. This extension at one side thereof is formed with a tapering socket or recess 11 to receive the inner end of a set screw 12 which is threaded in the holder 5. The die body 9 is further provided with a rectangular opening 13, extending longitudinally therethrough for a purpose which will be presently referred to.

The convex face of the body 9 has an outer annular or ring shaped area 14 upon which the name of the post office station or other indicia, indicated at 15, is formed in raised or embossed characters.

The entire space bounded by the walls of the rectangular opening 13 through the die body is completely filled or occupied by a plurality of type carrying bars. In the present instance I have illustrated such type bars in Figures 1, 7 and 8 of the drawing as consisting of hour, day, month and year type bars, designated by the numerals 16, 17, 18 and 19, respectively. These bars are releasably secured within the opening of the die body in the relative arrangement seen in Figure 1 of the drawing, by means of the instrumentalities to which I shall now refer.

The bar 16 which marks or stamps the hour of mailing is provided in one side face thereof with a socket or recess 20 to receive a stud or pin 21 projecting from the opposed face of the bar 17 which stamps or marks the day of the month. Thus these two type bars when arranged in the opening 13, are connected together for movement as a unit. The bars 16 and 17 are further provided with transverse openings 22 and 23 respectively, extending entirely through said bars and registering with each other. These registering openings, when the type bars are in printing position, are also in alinement with openings indicated at 24 provided in the die holder 5 and through such alined openings the locking pin or rod 25 is adapted to be inserted.

The die body 9 is provided at one side of the rectangular opening 13 with a longitudinally extending recess 26 opening at one of its ends upon the end face of the boss or extension 10 and closed at its other end. In the die body at the latter end of the recess 26, a pin 27 is fixed, said pin having a flange or head 28 flush with the end face of the die body. Surrounding the pin 27 between the head 28 thereof and the base wall of the recess 26, a coiled expansion spring 29 is ar-

ranged. The hour printing type bar 16 in the side face thereof opposite to the socket 20 is centrally provided with a longitudinally extending concave groove or channel 30 which opens on the end of said type bar. When the type bars 16 and 17 are assembled and inserted into the opening 13 of the die body, as seen in Figure 1, the spring 29 is engaged by the horizontal shoulder 31 at the inner end of the channel or groove 30 and as the type bars are moved inwardly this spring is compressed as seen in Figure 5 of the drawing, until the registered openings 22 and 23 of the type bars come into register with the openings 24 in the die body so that the locking pin 25 can be inserted through such registering openings and thus retain the type bars in their assembled positions within the die body.

The pin 25 when inserted also extends through an opening 32 in the year printing type bar 19 which is arranged in position within the opening 13 previous to the assemblage of the type bars 16 and 17 therein. In addition to the opening 32, the type bar 19 is provided with a second transverse opening 33. The month printing type bar 18 is arranged in line with the day type bar 17 and between the hour and year type bars and is provided with a threaded aperture 34. The latter type bar is held in assembled relation with the bars 16, 17 and 19 by means of the screw 35 which is loosely disposed through an opening 36 in one side of the type body 9 and also extends loosely through the opening 33 in the type bar 19, the inner end of said screw having threaded engagement in the aperture 34.

From the above description it will be seen that the type bars 16 and 17 which are most frequently changed, and particularly the type bar 16, can be easily released and removed from the die body and replaced by other type bars, simply by withdrawing the pin 25. When this pin is withdrawn or retracted from engagement in the openings 22 and 23, both of said type bars by reason of their connection by the stud or pin 21, are projected outwardly by the expansion of the spring 29 and beyond the convex printing face of the die body so that said type bars can be easily grasped between the thumb and finger and removed. The other two type bars 18 and 19 which are less frequently changed, remain secured in position within the opening 13 by the screw 35. After new type bars 16 and 17 have been inserted in the die body in the manner above explained, the locking pin 25 is again inserted in locking position and the device is in condition for use. In this manner, it will be apparent that by reason of my present improvements, the change in the hour and day printing type bars can be very quickly made, and it also becomes unnecessary to employ a tool or

implement as an aid in extracting the type bars from the opening of the die body, thus obviating the possible mutilation of the type characters. I have above referred to one means for assembling the two type bars 16 and 17 in connected relation and for automatically projecting the same from the body of the die when the locking pin is withdrawn. Obvious variations of this arrangement may, however, occur to the skilled mechanic and other provisions for mounting and arranging the projecting spring 29 devised. Such variations of mechanical details are however to be construed as within the contemplation of my present improvements and since it is manifest that the essential characteristics of this invention might be incorporated in numerous other alternative structures, it is to be understood that the privilege is reserved of resorting to all such legitimate changes in the form, construction and arrangement of the several parts as may be fairly embodied within the spirit and scope of the invention as claimed.

25 I claim:

1. In a printing die, a die body having a printing face and an opening extending through said die body, provided with a recess formed in one of the walls of said opening; interlocking type bars adapted to be assembled within said opening with their type characters in proper relation with the printing face of the die body, means for releasably locking the type bars within the opening of the die body, and means carried in the recess of the die body and engaging one of said type bars automatically acting to project the type bars from one end of said opening when the bars are released.

40 2. In a printing die, a die body having a printing face and an opening extending through said die body, a plurality of sets of type carrying bars adapted to be inserted within said opening with their type characters in printing relation with respect to the printing face of the die body, means acting to resist the movement of the one set of type bars to such position and to project said set of type bars from said opening, and manually operable means for releasably locking said set of type bars in assembled position in the die body against the action of such resisting means independently of the other set of type carrying bars.

55 3. In a printing die, a die body having a printing face and an opening extending through said die body, a plurality of type carrying bars, coacting means carried by certain of said bars to hold the same in assembled relation for movement as a unit into and out of the opening in the die body, means yieldingly resisting the movement of said assembled type bars into said opening to a position with their printing char-

acters in proper relation with the printing face of the die body, manually operable means to releasably lock the assembled type carrying bars within the opening of the die body against the action of such resisting means and additional means for releasably locking the remaining type bars in assembled position within said opening.

4. In a printing die for stamp cancelling machines and the like, a die body having a printing face and an opening extending through said die body, a plurality of type carrying bars adapted to be inserted within said opening with their printing characters in printing relation with the printing face of the die body, means acting to yieldingly resist the movement of certain of the type bars to such assembled position, means for releasably locking said type bars in properly assembled position against the action of such resisting means, and additional means for releasably locking the remaining type bars in assembled position within said opening.

5. In a printing die, a die body provided with an opening therethrough surrounded by a printing face, a type bar adapted to be inserted in said opening with its type character in proper printing relation with the characters on said annular printing face, means for detachably locking said type bar within the opening of the die body, and means mounted in one of side walls of said opening and co-acting with the type bar to project the latter from one end of said opening when the locking means is withdrawn.

6. In a printing die, a die body having an opening therethrough surrounded by a printing face, a type bar adapted to be arranged within said opening with its type character in printing relation with the characters on said printing face, a spring mounted in one of the side walls of said opening and acting against said type bar to resist its movement into said opening, and means for releasably locking the type bar in assembled relation to the die body against the action of said spring.

7. In a printing die, a die body having an opening therethrough surrounded by a printing face, type bars provided with co-acting interlocking means adapted for insertion into said opening with their type characters in printing relation to the characters on said printing face, means for releasably locking said type bars in assembled relation with the die body, and means mounted in the wall of said die body at one side of said opening and acting upon one of said type bars to automatically project the interlocked type bars from one end of the opening when said bars are released.

8. In a printing die, a die body having

an opening extending therethrough and surrounded at one of its ends by a printing face of the die body, a type bar adapted for insertion into said opening and having a type character on one end for arrangement in printing relation with the type characters on said printing face, said type bar being provided with a shoulder on one of its side faces, means carried by the die body to co-act with said shoulder to yieldingly resist the

movement of the type bar to its assembled position within said opening, and means for releasably locking the type bar in such assembled position against the action of said resisting means.

15

In testimony that I claim the foregoing as my invention, I have signed my name hereunder.

GEORGE H. REOCH.
